UNITED STATES PATENT OFFICE.

HENRY K. SOUTHLAND AND CHARLES F. WARREN, OF WASHINGTON, D. C.

COMBINED ADVERTISING MEDIUM AND CARD OR TICKET HOLDER.

SPECIFICATION forming part of Letters Patent No. 350,022, dated September 28, 1886.

Application filed February 11, 1886. Serial No. 191,634. (No model.)

To all whom it may concern:

Be it known that we, HENRY K. SOUTHLAND and CHARLES F. WARREN, citizens of the United States, residing at Washington, in the 5 District of Columbia, have invented certain new and useful Improvements in a Combined Advertising Medium and Card or Ticket Holder; and we do declare the following to be a full, clear, and exact description of the invention, such as will enable others skilled in the art to which it appertains to make and use the same, reference being had to the accompanying drawings, and to the letters and figures of reference marked thereon, which form a 15 part of this specification.

Our invention relates to combined advertising-pamphlets and card or ticket holders, and is designed to combine the two in a convenient form for distribution by railroad-ticket 20 agents and others in disbursing tickets. The ticket-holder is placed on the outside of the cover or back, and holds the ticket in such a way as to be readily accessible, legible, and removable, while retaining it with sufficient 25 security to prevent loss.

As now practiced railroad-tickets are sold in envelopes, which, while they hold the ticket against soiling, do not prevent it from being crumpled, and add nothing to the size or weight 30 of the ticket, thereby rendering it liable to become displaced or lost; nor do envelopes afford a permanent holder, or one that is likely to attract any attention when placed among other papers.

Our invention is designed to take the place 35 of the envelopes now in use, and to cure the difficulties arising from such use in positions as herein indicated; and while our invention gives a more readily discoverable character to 40 the ticket-holder and adds permanency and durability thereto, it at the same time affords a means for inserting any number of advertisements in a very readable way, and in such shape as will be likely to attract the attention 45 of the ticket holder or purchaser. These advertisements can be made to be of value to the traveler, as we design placing advertisements in the pamphlet or little book which shall relate to matters at his destination—as, for instance, when a ticket is sold in New York for 50

Washington, the book or pamphlet on which it will be held and delivered to the purchaser will contain Washington advertisements of hotels, boarding-houses, places of business or amusement, lines of travel, and similar matter likely to be of interest and service to the traveler; and, if desired, a brief description of the town or city of destination and of the principal points of interest therein may be added to the advertisements, thus making the 55 ticket-holder an invaluable adjunct to the ticket.

In constructing our device we prefer to have at least one of the backs or covers of the book stiff, though both may with good effect be stiff, 60 and preferably are so. To the stiff or inflexible back we secure the ticket-holder, which we form of wire, and so construct as to have supports for the ticket at the bottom on both sides and a centrally inwardly-pressing spring 70 portion for holding the ticket securely in place. The top of the spring portion may have a curved guide extending out slightly, to the more readily receive and guide the ticket into place. This construction not only holds the ticket in position, so that it can be readily seen and its contents or the matter upon it readily perused, but it also makes a reliable holding means and prevents the ticket from dropping out, the 75 ends of the loops, which lie upon the outside 80 of the back, serving as raised supports for the ticket, while the ring or spring portion clamps or presses the ticket in against the back.

The following detailed description of our invention will enable others the more readily to 85 understand the same.

The accompanying drawings illustrate what we consider to be the best means for carrying our invention into practice.

Figure 1 is a front elevation of our combined 90 device. Fig. 2 is a similar view showing a ticket in place. Fig. 3 is a side elevation or edge view.

Similar letters of reference indicate corresponding parts in all the figures where they 95 occur.

A is the book or pamphlet, on the pages and covers of which the advertisements and other reading-matter are to be placed. To one of the covers *a* the ticket-holder is secured. This 100

ticket-holder is preferably made of a single piece of wire or other elastic springy material. The ends are fastened to the cover by being inserted through the same from the outside, 5 extended along the inside of the cover, then passed back and extended for a suitable distance down the outside of the cover, as shown by the loop *b* in Fig. 3. Between these two end fastenings the wire is bent to form the 10 bottom supports, *b' b'*, and the upwardly-extending central spring portion, *B*, whose natural elasticity, due to the manner in which it is constructed, presses inward toward the cover. A loop or double ring is made of the wire at 15 this point, as shown in Fig. 2; or it may be twisted in any other desired or convenient form, one such being shown in Fig. 1. It is evident that the form of the clamp at this point is not essential. It is also evident that the 20 clamp ends may be secured to the cover in many other ways besides that shown, and we would not be understood as limiting ourselves to the form of clamp in any particular, except as to having a spring portion and support or 25 supports for the lower edge of the ticket.

In order to facilitate the insertion of the ticket under the portion *B*, we provide a slightly outwardly projecting portion or guide, *B'*, which may be made by simply bending or 30 curving the top of part *B* outward, as shown in Fig. 3, or by making a loop or teat in the wire at this point, as shown in Figs. 1 and 2. Either form will serve to guide the ticket into place.

35 As shown in the figures, the holder affords a central open space below, where the ticket may be reached and pushed upward when it is desired to remove it. This space is marked *B**. The portions of the loops *b* and of the 40 wires of the device which rest upon the exterior of the back form side supports for the

back of the ticket, and the ring or spring portion *B* presses the ticket in between these wires against the back of the book and firmly holds it. The ticket is marked *Z*.

We are aware that ticket and sample holders have before been attached to various articles for advertising purposes, and these we do not claim, broadly; but our invention differs from them and constitutes a novel and 50 convenient device for the purpose described.

Having thus described our invention, what we desire to claim and secure by Letters Patent is—

1. A combined advertising medium and 55 ticket-holder consisting of a book or pamphlet having a ticket-holder secured upon its cover, said ticket-holder being formed of wire bent upon itself to form a spring-clamp, and suitably shaped at the top to receive the ticket, 60 the free ends of the wire being bent to form supports or retaining portions at its bottom, and suitably fastened to the cover to secure the holder in place, substantially as described.

2. A combined advertising medium and 65 ticket-holder consisting of a book or pamphlet having a ticket-holder secured upon its cover, said ticket-holder composed of a single piece of wire bent upon itself to form a spring-clamp, and an outwardly curved or extended guide 70 on top, the free ends of the wire being bent to form supports or retaining portions at its bottom, and passed through the cover to secure the holder in place, substantially as described.

In testimony whereof we affix our signatures 75 in presence of two witnesses.

HENRY K. SOUTHLAND.
CHAS. F. WARREN.
